US00D943148S

(12) **United States Design Patent** (10) **Patent No.:** **US D943,148 S**
Chang et al. (45) **Date of Patent:** **** Feb. 8, 2022**

(54) **CAP FOR AEROSOL GENERATING DEVICE**

(71) Applicant: **PHILIP MORRIS PRODUCTS S.A.**,
Neuchatel (CH)

(72) Inventors: **Wei Chia Chang**, Geneva (CH);
Jeffrey Tung, San Francisco, CA (US);
Hankak Lee, Seocho-gu (KR)

(73) Assignee: **PHILIP MORRIS PRODUCTS S.A.**,
Neuchatel (CH)

(**) Term: **15 Years**

(21) Appl. No.: **29/692,682**

(22) Filed: **May 28, 2019**

(57) **CLAIM**

The ornamental design for a cap for aerosol generating device, as shown and described.

DESCRIPTION

FIG. 1 is a front and top perspective view of a cap for aerosol generating device;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

(Continued)

The broken lines in the drawings depict portions of the cap for aerosol generating device that form no part of the claimed design.

1 Claim, 7 Drawing Sheets

Related U.S. Application Data

having an international filing date of Sep. 14, 2017, now Pat. No. Des. 862,793.
